Primary Examiner — Karen S Acker*Assistant Examiner* — Elizabeth S Ko(57) **CLAIM**

The ornamental design for a shower curtain rod end cap, substantially as shown and described.

DESCRIPTION

FIG. 1 is a front perspective view of shower curtain rod end cap, showing my new design;

FIG. 2 is a rear view thereof;

FIG. 3 is a front view thereof;

FIG. 4 is a left side view thereof;

FIG. 5 is a right side view thereof;

FIG. 6 is a top view thereof; and,

FIG. 7 is a bottom view thereof.

The broken lines and areas within them depict portions of the shower curtain rod end cap that form not part of the claimed design.

1 Claim, 7 Drawing Sheets(56)
